UNITED STATES PATENT OFFICE.

DANIEL MCFARLAN MOORE, OF NEW YORK, N. Y., ASSIGNOR TO THE MOORE ELECTRICAL COMPANY, OF SAME PLACE.

PHOSPHORESCENT-ELECTRIC-LIGHT CONDENSER AND ACCUMULATOR.

SPECIFICATION forming part of Letters Patent No. 548,575, dated October 22, 1895.

Application filed January 24, 1895. Serial No. 536,037. (No model.)

To all whom it may concern:

Be it known that I, DANIEL MCFARLAN MOORE, a citizen of the United States, and a resident of New York, county and State of New York, have invented certain new and useful Improvements in Phosphorescent - Electric - Light Condensers and Accumulators, (Case No. 16,) of which the following is a specification.

10 This application forms one of a series relating to the production of phosphorescent electric light on the Moore principle of the disruptive discharge of dynamic currents *in vacuo*.

15 The present invention relates generally to the accumulation of the light thus produced by the action of condensing the electricity, accompanied by the light, upon metallic surfaces, and by the use of insulating media.

20 The invention relates also to certain modifications of the generic invention.

Figure 1 is an elevation, partly in diagram, illustrating the manner of carrying my invention into effect. Fig. 2 shows means whereby the electricity may be so condensed at a desired point as to produce light where no light had been before produced without a condenser. Fig. 3 is a view, partly in diagram, of what may be conveniently termed a "vacuum" converter. Fig. 4 shows, partly in diagram, what may be called a "Leyden-jar" lamp or means for storing light. Fig. 5 is a view, partly in section and partly in diagram, of a modification of a part of that which is shown in Fig. 4.

25 In Fig. 1, 1 is an evacuated inclosure in the form of a bulb having a large rounded end covered with a metallic coating 2 and 3, located, respectively, on the inner and outer surfaces and formed of a metallic paint or tin foil, or any other metallic foil, or of any form of material, as long as it is an electric conducting coating.

30 4 is an electric conductor extending from the small end of the bulb and terminating in contact with the inner coating 2. This conductor 4 forms an extension from an electric circuit of the generator 5, passing through and including a magnet 6, a spring terminal 7, having an armature within inductive relation of the magnet and located within the evacuated bulb 1, the fixed terminal 8, and the

conductor 9, which completes the circuit to the generator.

From the construction it will be understood that upon the passage of an electric current from the dynamo 5 the current will be rapidly interrupted at the terminals 7 and 8, and in view of pending applications upon a similar class of inventions already filed by me it should be understood that the wire 4 becomes luminous with a comparatively low dynamo and that the whole bulb becomes a light producer and the vacuum is about that which would be produced by an ordinary mechanical air-pump. The outside coating 3 is connected to earth 10. In view of the glass partition between the two coatings and in view of the electric potential of the wire 4 the electricity and the light effect caused thereby becomes accumulated and increased, especially by having a good earth connection between the coating 3 and the ground 10.

Referring more particularly to Fig. 2, 1' is a glass tube properly exhausted and having the vibratory terminals as before, 7 and 8, which in this instance may be included in a circuit, as in Fig. 1, or, as shown in Fig. 2, they may be included in a different circuit from that of the magnet 6. They are shown in form as in a secondary circuit of an induction-coil 6', whose primary is in circuit with the generator 5'. The magnet 6 is alternately magnetized and demagnetized in view of the rotary interrupter 11 in circuit with the magnet 6 in Fig. 2. The conductor 4' is shown as carried from the terminal 7 throughout the length of the tube and inside thereof and then outside in such a manner as to be included in circuit with the secondary coil of the transformer 6' and with the terminals 7 and 8.

If the circuits are arranged and completed as described, so that the secondary current may pass through the terminals and so that the magnet 6 produces rapid interruptions at the terminals 7 and 8, then the light will appear as a brilliant illumination around the whole length of the wire 4'; or if the currents are not sufficiently strong, or if the tube 1' is too long in proportion to the electrical dimensions of the electrical features, then will light only appear at the two ends of the tube, while it will be dark between the ends; but if one grasps the central part of the tube by his

hand, as represented at 12, an immediate production of light will appear as radiated between his fingers and in the neighborhood of his hand within the tube. On taking away 5 the hand the light ceases, but still remains at the ends of the tube. This may be repeated as often as desired. It is thought that the hand represents either an earth connection, or else a large mass of matter adapted to be- 10 come electrified and thereby produce a condensing action, for this same effect is produced by placing near the tube a large mass, and it is produced by actually surrounding and touching the tube with any conductor or 15 semi-conductor having a good or bad earth connection.

In Fig. 3, as in Fig. 1, the evacuated inclosure is represented by 1, and the remaining elements, in so far as they are shown, are indicated by the same reference-numerals. In this case the coatings 2 and 3 are omitted and the conductor 4 is extended through the wall of the inclosure and terminated by a metallic ball 13, from which, when the device is in operation, 25 sparks may be obtained, even if the magnet 6 is not a very powerful self-induction device; but, of course, the higher the electromotive force in the circuit 9 the greater the sparks which may be obtained at the ball 30 13 by bringing to it a conductor or semi-conductor not similarly electrified. This device may be employed for charging Leyden jars or similar condensers, and for performing the same functions as possessed by the Ruhmkorff 35 coil or the Holtz frictional machine. The manner of modifying this device for the purpose of producing greater static effects than by increasing the electromotive force in the circuit 9 consists in increasing the length of 40 the wire 4 by coiling it or by doing both things.

In so far as the parts correspond to those shown in Fig. 1 the same are indicated by the same numerals in Fig. 4. The conductor 4 is electrically connected by springs 14 to the 45 inner coating 2. As in Fig. 1, it is extended to the wall 2 and terminated by the metallic coating 15, and the coating 3 is connected to the earth 10. 1" is a glass bulb which surrounds the device, so that an evacuated space 50 may be the location of the ball 13 and the outer coating 3. The coating 15 is located on the inner surface of the bulb 1", so that it is opposite at least a portion of the coating 3. Between the coatings 15 and 3 are suspended, 55 by flexible cords 16, light-balls 17, which may be increased in number, the more the better, and which may be suspended from radial arms 18, supported by a ring 19, which is fixed upon the tube 1 within the evacuated bulb 1".

60 After the current has been turned off from the dynamo 5, as often takes place at the time of accidents, when lights suddenly go out in dwelling-houses, and as takes place after a certain hour of the night, this device will 65 continue to give out light because of the electrical energy stored therein. In the same manner that a storage-battery is a means for

storing up new chemical compounds for producing electricity, so this may be called a device for storing light, because it accumulates 70 electricity for producing light. The operation of the device after once stored is automatic. The balls 17 are attracted to the coating 15 and become charged with a load of 75 electricity of one polarity and of the same polarity as that upon the coating 15. Then the balls, after being fully charged, are repelled by virtue of the principle that like electricities repel and unlike attract, and at the same time they are attracted by the same 80 principle to the coating 3, where they give up their charge to the earth. They are then again attracted to the coating 15, and so they move back and forth very rapidly, each time producing sparks, which may be said to exist 85 throughout the vacuum, producing brilliant illumination. The balls 17 move very rapidly and very irregularly, so that the average effect is a practically continuous light, and as the balls are made of elder-pith they produce 90 no sound, although they vibrate back and forth very rapidly.

In order to keep the light stored until wanted the earth connection at 10 may be completely broken at the same time that the dynamo 5 is cut off. When the light is wanted the earth connection may be made, and the length of time that the light will be given out will depend only upon the dimensions of the device; but even with a small one it takes a 100 long time for the balls 17 to discharge the accumulated electricity.

The invention may be modified here and there without departing from the spirit of the invention. For example, it makes no difference from which terminal, 7 or 8, the conductor 4 extends.

I call the device shown in Fig. 3 a "vacuum" converter, because it transforms dynamic currents of comparatively low potential into electricity of very much higher potential. At the same time the device falls under the name of an "accumulator," because the ball 13 collects electricity upon its surface in proportion to the size of the surface, and the same may be 115 transferred to translating devices which are to be operated by the static electricity.

The opaque coatings 2 and 3 do not cause the loss, materially, of the light, because the surface of the coating 2 is arranged upon a 120 concave, spherical, or conical surface, and therefore the light is radiated into space in a concentric manner. The form of this surface may be changed to suit the requirements of the case.

125 It is evident that a modification of the invention shown in Fig. 4 may consist in having the tube 1" communicating with the tube 1, so that both may be exhausted together and considered as one evacuated space. This construction, omitting the electrical features, is shown in Fig. 5, the point of exhaustion and sealing being at 19, the tube 1 being open at the lower end 1'" and preferably closed at the

other end. The rest of the construction will be substantially as represented in Fig. 4, except that it should be stated that the tube 1 may be held by a ring 20 to the tube 1".

5 I claim as my invention—

1. A phosphorescent electric light accumulator, consisting of the combination of an evacuated insulating inclosure, vibratory electric terminals therein, metallic coatings upon portions of the inner and outer surfaces of the insulating material of the inclosure and opposite each other, an electric conductor connecting the inner coating with the circuit of the terminals, and an electric conductor connected to ground.

2. A phosphorescent electric light accumulator, consisting of the combination of an evacuated insulating inclosure, vibratory electric terminals therein, metallic coatings upon portions of the inner and outer surfaces of the insulating material of the inclosure and opposite each other, and an electric conductor connecting the inner coating with the circuit of the terminals.

25 3. A vacuum converter consisting of the combination with an evacuated inclosure having separable contacts normally touching each other and included in an electric circuit of an electric conductor extending throughout the evacuated space through the wall of the inclosure and terminated by a ball or mass of material.

4. A phosphorescent electric light accumulator consisting of the combination of concentric evacuated inclosures, the first having inner and outer metallic coatings, and containing vibratory electric contacts within sparking distance of each other, and electrically connected to the inner coating of the 40 first inclosure, which coating is also connected to the inner coating of the second inclosure, and flexibly suspended balls located between

the last named coating and the outer coating of the first inclosure.

5. A phosphorescent electric light accumulator, consisting of the combination of an evacuated inclosure, containing a condenser made of an insulating sheet and metallic coatings on opposite sides thereof, vibratory electric contacts normally touching each other 45 and electrically connected to the same coating and carried around the insulating material to points opposite the other coating, and means for intermittently and gradually discharging the condenser within the vacuum.

6. A phosphorescent electric light accumulator consisting of the combination of an evacuated inclosure containing a condenser made of an insulating sheet, and a metallic coating on opposite sides thereof, a device for 50 charging the condenser with electricity, and means for slowly discharging the condenser at points within the vacuum, for the purpose as set forth of producing light.

7. A phosphorescent electric light accumulator consisting of the combination of an evacuated tube, separable electric contacts, normally touching each other, located at one end of the tube and having a return wire passing throughout the length of the tube 60 and located in circuit with the secondary coil of a given electric transformer 6', means for causing the terminals to vibrate to and from each other, and a conductor or semi-conductor located at or near the tube.

In testimony that I claim the foregoing as my invention I have signed my name, in presence of two witnesses, this 8th day of January, 1895.

DANIEL MCFARLAN MOORE.
